UNITED STATES PATENT OFFICE.

WILLIAM MENDHAM AND CYRUS CHAMBERS, JR., OF PHILADELPHIA,
PENNSYLVANIA; SAID MENDHAM ASSIGNOR TO SAID CHAMBERS.

IMPROVEMENT IN TURN-SHEET FOLDING-MACHINES.

Specification forming part of Letters Patent No. 222,523, dated December 9, 1879; application filed May 8, 1879.

To all whom it may concern:

Be it known that we, WILLIAM MENDHAM and CYRUS CHAMBERS, Jr., of Philadelphia, in the State of Pennsylvania, have invented an Improvement in Turn-Sheet Folding Machines; and we do hereby declare the following to be a full and correct description of the same, reference being had to the accompanying drawings, in which—

Figure 1 is a plan or top view of our improved machine. Fig. 2 is a transverse vertical section on line $x x$ of Fig. 1. Fig. 3 is a vertical section on line $y y$ of Fig. 1, on an enlarged scale, showing the tapes arranged for turning the sheet over before receiving the third fold. Fig. 4 is a similar section on the same line, with the parts arranged for making the fold without turning the sheet over.

The same letter indicates the same part in all the figures where it occurs.

Our improvement consists in providing the ordinary sixteen-page Chambers book-folder with a device by which, when desired, the twice-folded sheet may be turned over before receiving the third fold, so that said fold shall be given in the reverse way from that given in the ordinary machine.

When a sheet of eight pages is to be folded three times, and so that the title is to be on the outside, where it can be seen, it is necessary that the last fold should be made in the reverse way from that used in folding a regular sixteen-page sheet. To accomplish this the sheet, after being twice folded, requires to be turned over before receiving the last fold, in order that the blade may strike it between the folding-rollers upon the opposite side.

To enable the machine to perform this operation is the object of our improvement.

The general construction of the machine is that of the well-known Chambers folders, and needs no particular description. The sheets are fed, folded, and delivered in the ordinary way.

To the original machine we have added the roller A, carrier-roller C, small rollers D, and movable stops B E, attached to rock-shafts M N, and operated by levers K L, all as shown in the drawings, and most distinctly in Figs. 3 and 4.

A is the roller, around and over which the twice-folded sheet is carried in the act of turning.

C is the carrier-roller, which, by friction, carries the sheet over roller A.

B is the last stop, which, in the ordinary order of folding, is in the position shown in Fig. 4, and arrests the folded edge of the sheet prior to the reception of the third fold, but can, by means of lever L, attached to the end of rock-shaft N, to which stop B is attached, be turned down out of the way of the sheet, into the position shown in Fig. 3, when necessary.

E is a movable stop, used to arrest the sheet after it has been turned over, but which can be turned down out of the path of the sheet, when required, by means of lever K on the end of the rock-shaft M, to which the stop is attached. When turned down it occupies the position shown in Fig. 4.

The tapes $t t$, for the ordinary folding, have the arrangement shown in Fig. 4, passing around rollers F, I, and I', and below roller A. When the machine is used to turn the sheet these tapes have the arrangement shown in Fig. 3.

The operation of the machine when used in ordinary folding is illustrated in Fig. 4. The sheet, having passed the rollers G F, receiving its second fold, is carried by the tapes till its folded edge strikes the stop B, which is in the upright position and in the path of the paper. The stop E, during this operation, is turned down out of the path of the sheet, to give it free passage. When thus arrested, the sheet is in position to be driven by knife J between the third pair of folding-rollers to receive its third and last fold.

When it is desired to turn the sheet before receiving the third fold, the tapes are arranged as shown in Fig. 3, and the twice-folded sheet, passing from rollers G F, is carried by tapes t up to the top of roller A, and under the carrying-roller C; thence around roller A and over rollers D, till its folded edge comes into contact with stop E, which is in its upright position and in the path of the paper. The stop B, during this operation, is turned down out of the path of the sheet. When thus ar-

rested by stop E the sheet, having been turned upside down, is in position to receive its third fold in a direction the reverse of that in which the fold would be given by the arrangement shown in Fig. 4.

The folding-blade J has sufficient range of motion to enable it to rise above the inclined tapes and allow the sheet to pass under it.

What we claim, and desire to secure by Letters Patent, is—

1. In a sixteen-page book-folding machine, the device herein described for converting the machine from an ordinary sixteen-page folder to a machine capable of turning the twice-folded sheet upside down prior to its receiving the third fold, the same consisting of the combination of the tapes *t*, rollers A C, and movable stops B E, all arranged and operating substantially as and for the purpose described.

2. A book-folding machine provided with mechanism, as described, for converting it at pleasure from an ordinary folder into a turn-sheet folder, by which the sheet is turned over before receiving any particular fold of a series, so that said fold shall be made in the reverse way from that given by an ordinary machine, all substantially in the manner set forth.

The above specification of our said invention signed and witnessed, at Philadelphia, this 11th day of March, A. D. 1879.

WILLIAM MENDHAM.
